ROAD ILLUMINATION

Filed Nov. 2, 1926

UNITED STATES PATENT OFFICE.

NICHOLAS M. MICHAILOVSKY, OF NEW YORK, N. Y.

ROAD ILLUMINATION.

Application filed November 2, 1926. Serial No. 145,753.

The principal objects of this invention are to secure the proper illumination of roadways without throwing blinding or confusing lights into the eyes of motorists and 5 pedestrians.

These objects are attained by confining the light to the actual surface to be illuminated and in such a way that the source of the light will not be observable at the normal level of 10 the eyes to a pedestrian or motorist.

Other desirable objects and the novel features of construction, combinations and relations of parts by which the same are attained are set forth in the following specification.

The drawings accompanying and forming part of this specification illustrate both the problem in illumination and several of the solutions accomplished by this invention.

20 Thus,

Figure 1 is a view illustrating diagrammatically how for automobile driving, the beam of light must be thrown forwardly a considerable distance in front of the car and 25 how the entire top of this beam must be shielded to a point considerably in advance of the car to hold the light down to a horizontal plane below the eyes of possible observers.

30 Figure 2 is a side elevation of a multitude light shield construction offering one practical solution of the problem.

Figure 3 is a top plan view of this particular form of the invention.

35 Figure 4 is a front view of this particular lamp.

Figures 5 and 6 are front views of modified forms of this lamp.

The ideal condition to be attained in road 40 illumination, as illustrated in Figure 1, is to direct all the light down onto the roadway in a beam far enough ahead of the vehicle for safe driving and to shield all that light at the source above a horizontal plane repre-

45 sented by the line H, below the normal level of the eyes of pedestrians and oncoming motorists. To provide such a shield would require that the beam emanating from the lamp 45 1 be covered by a substantially triangular

50 guard extending forwardly from the top of the lamp at C to a point B intersecting the horizontal plane H and having its lower edge extending forwardly horizontally from a point D at the bottom of the lamp. Considering that the beam strikes the roadway at a

point A, say fifty feet in advance of the car, that the height on the line E-C from the roadway to the top of the lamp is forty inches and that an eight inch reflector is used (the distance C-D), the distance C-B becomes 60 approximately ten feet. This is established by the formula that

$$B.C = \frac{A \cdot C \times C \cdot D}{C.E.}$$

65 derived from the two triangles A, C, E and B, C, D. A shield of such dimensions is, of course, impracticable.

From the formula, it will be seen that B-C can be reduced by increasing C-E, the height above the roadway or by reducing A-C, the length of the beam or C-D the vertical connection of the beam at its source. The range of the light should be at least from twenty-five to fifty feet and the height of the light 70 above the roadway is more or less fixed by automobile design. Reducing the other factor, the distance C-D, that is, the height of the reflector, to four inches which is about the smallest now available, the shield 75 required corresponding to the distance C-B would still be over sixty inches and hence impractical.

80 In the forms of the invention illustrated in Figures 2 to 6, the difficulty is solved by dividing the beam of light horizontally into six different sections and providing a miniature shield for each one of those sections. The lamp, indicated at 2, therefore has its beam divided by the shields 3, 4, 5, 6, 7, 8 85 parallel to the beam, into sections 3^a, 4^a, 5^a, 6^a, 7^a, 8^a, each of which is directed down onto the roadway and is covered so as to have the source invisible at a point above the horizontal plane H. These shields are relatively 90 short, about six to eight inches for the full size lamp and so come within practical requirements, both from the standards of utility and appearance.

These shields are inclined at the top in 95 accordance with the inclination of the beam or section of beam which they shade and have their lower edges horizontal. The upper shield 3 is shown rounded in accordance with the curvature at the top of the reflector and the other shields are indicated as flat and as having side wings 9 dependent from the edges thereof and extending downwardly from the flat inclined planes of the tops of the shields to the horizontal planes, consti- 100 105 110

tuting the lower edges of the shields. The shields thus form a partially nested set of relatively small pointed visors which may be attached to the lamp housing as a unit, or 5 separately as desired.

The size, arrangement and number of the side wings 9, as well as other details of construction may vary. For example, only two side wings may be employed as indicated at 9^a 10 in Figure 5, these extending from the top reflector downwardly far enough to shield the edges of the entire set of shields and terminating on a lower horizontal line corresponding with the lower horizontal edge of the reflector 8 in Figure 2. The shields may have rounded or straight front edges as shown in Figure 3.

In the modification shown in Figure 6, only two wings 9^b are provided but these 20 spring from the edges of the third shield instead of from the top shield, the two upper shields being closed in at the sides and the two lower shields being open at the edges beneath the wings 9^b.

25 The under surfaces of the shields are preferably reflective so that said shields, with the side wings, will cast a certain amount of light for illumination of the sides of the road.

When viewed from in front, under normal 30 conditions, that is, with the eyes at an ordinary level and the beam projected down on the road, no direct light from the lamp will be visible to the observer and while the road will be fully illuminated, the source of 35 light will be concealed.

By this invention other drivers and 40 pedestrians on the road or at the sides of the road are protected from glare and both sides of the road are equally illuminated. This 45 absence of glare enables bright driving lights being used in city streets. The symmetrical shielding of the light on both sides also prevents the light from being thrown into

the eyes of the drivers of oncoming cars on curves and turns in the roadway.

45 The light shields of this invention may be applied to ordinary headlights.

The shields also may be applied to spot-lights. A convenient method of applying the invention to existing lamps is to form the 50 base of the shield as a clasp ring adapted to encircle the rim of the lamp housing, enabling the shield to be quickly attached directly to the front of the lamp.

55 What is claimed is:

In roadway illumination, the combination with a light source supported above the roadway a distance less than the normal level of the eyes of pedestrians on the roadway, a reflector directly behind said light source and arranged to project a forwardly and downwardly inclined light beam onto the roadway a considerable distance in front of the source, of a plurality of forwardly projecting thin metallic shields arranged in closely spaced superposed relation in front of the light source and each parallel with the downwardly and forwardly inclined rays of the light beam and extending forwardly far enough to entirely cover that part of the reflector from which said shield receives its light, as viewed from in front with the eyes on the plane of those of a pedestrian on the roadway, side wings flaring downwardly and outwardly from the side edges of the shields substantially to a horizontal plane in line with the forward edges of the shields, whereby the light from the reflector will be concentrated on the roadway at a useful distance in front of the source with side light illumination from beneath the wings and none of the direct light will be visible to pedestrians or drivers on the roadway.

70 In witness whereof, I have hereunto set my hand this 14th day of October, 1926.

75 NICHOLAS M. MICHAILOVSKY.
